UNITED STATES PATENT OFFICE.

GEORGE AMBORN AND GEORGE W. BUFFORD, OF NEW YORK, N. Y.,
ASSIGNORS TO J. H. WILLIAMS & COMPANY, OF BROOKLYN, NEW
YORK, A CORPORATION OF NEW YORK.

CHAIN PIPE-WRENCH.

SPECIFICATION forming part of Letters Patent No. 769,042, dated August 30, 1904.

Application filed April 19, 1904. Serial No. 203,880. (No model.)

To all whom it may concern:

Be it known that we, GEORGE AMBORN and GEORGE W. BUFFORD, both citizens of the United States, residing in the borough of Brooklyn, county of Kings, city and State of New York, have invented certain new and useful Improvements in Chain Pipe-Wrenches Having an Inclosed Chain-Receiving Passage, of which the following is a specification.

10 The present invention relates to wrenches which are designed for use in gripping and turning such articles as pipes and pipe-collars. These wrenches in general perform their gripping function by engaging the pipe or similar article between a fixed part or jaw of the wrench and a chain which serves to maintain the pipe in close relation to said jaw. That part of the wrench upon which the jaw is fixed may for convenience be called 15 the "head." The head is conveniently attached to a handle. There are provided means for securing the ends of the chain against motion in order that it may properly coact with the gripping-surface, as above described.

20 25 Our invention more particularly consists in certain improvements affecting the relation between the chain and the points of engagement which secure it against motion.

We may best describe our improvements 30 by referring to the accompanying drawings, which illustrate certain preferred forms.

In the drawings, Figure 1 is a side view of a wrench which has a pair of gripping-jaws oppositely disposed upon its head. It is shown 35 gripping a pipe. Fig. 2 is a top view of this wrench. Fig. 3 is a sectional view of the wrench along the line 3 3 of Fig. 2. Fig. 4 is a sectional view of the wrench along the line 4 4 of Fig. 2. Fig. 5 is a partial side sectional view showing a modification of the association of parts assumed in Figs. 1, 2, and 3. Fig. 6 is a top view of a wrench embodying 40 our invention which employs coacting gripping-surfaces. Fig. 7 is a sectional view along the line 7 7 of Fig. 6. Fig. 8 is a top view of a portion of the chain conveniently employed in the wrench shown in Figs. 6 and 7, said

chain presenting certain modifications of the chain shown in Figs. 1, 2, and 3.

For convenience of description the wrenches 50 shown in the drawings may each be divided into four parts—a handle A, a head B, a chain C, and gripping-surfaces D.

The handle A may be of any convenient form. It may be integral with the head B of 55 the wrench, as shown in Figs. 1, 2, and 3, or it may be made separately and attached to the head in any convenient manner—for example, as shown in Fig. 5 and in Figs. 6 and 7.

The head B may be of any serviceable form, 60 those shown in the drawings being selected as to their general features from the great number presented by the prior art. The head proper may be a single head, as shown in Figs. 1, 2, 3, and 4, the gripping-surfaces D 65 on opposite faces being removably attached thereto, or the gripping-surfaces D may be formed integral with the head. In another form the head B may consist of two separated parts constituting a double head, as shown in 70 Figs. 6 and 7, these parts bearing gripping-surfaces D, which are adapted to coact in pairs. In this case also these gripping-surfaces D may be formed integrally with the head or they may be severally or collectively removable. 75

A head having a double series of gripping-surfaces similar to those shown in Figs. 6 and 7 might conveniently be made in one piece instead of in separable parts. Moreover, both parts of the head (shown in Figs. 6 and 7) might be made integral with the handle A. It is readily apparent that various modifications might be applied in this connection without involving material departure from the general scope of our invention. The single 80 head (shown in Figs. 1, 2, 3, and 4) is preferred because it can be employed with a single-course chain to squarely embrace and grip a pipe or other article.

The chain C may be of any convenient form, 90 but is preferably of the flat-link single-course double-acting type and has projecting pintles throughout its length. At each end it bears a stop c of such size or shape that it will not pass

through a passage in which any other part of the chain may be moved easily. In Figs. 1, 2, and 3 the stop *c* is shown in a cylindrical form equal in length to the chain-pintles, but of such 5 diameter that it would be denied passage through a slot in which the said pintles would be easily received. In Figs. 6, 7, and 8 the stop *c* is shown conveniently in cylindrical form equal in diameter to the chain-pintles, 10 but of greater length, thereby being impossible of passage through an aperture which is but slightly wider than the length of a chain-pintle. The stop *c* may be of any sort which will comply with the requirements set forth 15 above, those shown herewith being merely preferred forms. The wrench is provided with a central transverse passage *d* of such character as to permit the chain *C* to slip easily through it until arrested by either of the stops *c*, which 20 are of such size or shape as to be denied entrance into said passage. This passage is closed on all of its sides, but is open at both ends. It is located back of the grip-faces on the head and is central with respect to a plane 25 which bisects the grip-faces of the single head or is intermediate between the pair of grip-faces shown in Figs. 6 and 7.

At the extremities of the passage *d* are seats 30 *e* for the stops *c*. These seats *e* receive the stops *c* and maintain them firmly in position against the stress applied to the chain in the performance of its gripping function. It is apparent that either end of the chain may be engaged in this way upon opposite sides of 35 the passage *d*, so that by the simplest adjustment the chain may be drawn from one face of the wrench to the other. In this manner one end of the chain is secured against motion during use of the wrench. The passage *d* 40 furnishes space for the sliding movement of the body of the chain, and it has communicating lateral grooves in which the projecting pintles travel. It is necessary, further, that the other end of the chain be fixed against 45 movement in order that the chain may be retained in its proper position, encircling the pipe to be gripped and maintaining said pipe in its proper relation to the gripping-surface on the head of the wrench. For this purpose 50 the wrench is equipped with locks *f* for the free end of the chain. They are preferably given the form of spaced hooks arranged in pairs to coöperate in retaining one of the projecting pintles of the single-course chain *C*, 55 which extends through the space between the hooks. Two pairs of locks *f* are provided on the wrench oppositely disposed on both faces of the wrench to correspond with the gripping-surfaces *D*. The locks are located 60 behind the chain-passage, so that the entire extent of the grip-faces on both sides are available for gripping purposes. Inasmuch as either end of the chain *C* may be engaged and secured in position by a seat *e*, it is desirable that whichever end is so secured the

other end shall also be capable of engagement at some point. This object is attained by the arrangement of parts already described and shown with particular clearness in Fig. 1. The above remarks apply with equal force to both 7c types of wrench shown in the present drawings, the type having a single head, Fig. 1, and the type having a double head, Fig. 6. The locks *f* (shown in Figs. 6 and 7) are built into the two separated head-pieces *B* of 75 that wrench. Obviously these might be formed integrally with the handle and might be located at various points other than the positions which they are here shown to occupy, so long as they permit the coöperation of the 80 chain with the opposite grip-faces. This observation is true in regard to the locks *f* shown in the other figures. For example, the locks shown in Fig. 5 might be integral with the handle *A*. Any modification such as we 85 here suggest would in no way avoid our present invention. The locks *f* are conveniently spaced apart a sufficient distance to permit the easy introduction of the chain between them, as shown in Fig. 2. 90

The gripping-surfaces *D* are preferred to be in the form of serrated jaws, as shown in the present drawings. In Figs. 1, 2, 3, 4, and 5 the gripping-surfaces *D* are given the form of independent removable jaws. One 95 form possible for these jaws and a convenient mode of attachment to the head are clearly shown and described in a companion application thereto of Amborn and Chase, filed concurrently herewith, Serial No. 203,877. These 100 jaws might be on a single wrench composed of a single piece bearing two separately serrated surfaces. Separable jaws *D*, such as are shown in Figs. 1 and 3, are particularly desirable when the handle and head of the 105 wrench are formed integrally for reasons set forth in the above-named Amborn and Chase application which are unnecessary to be enumerated here. The style, form, mode of attachment, and general character of these gripping-surfaces *D* might be altered in a great 110 number of ways without necessitating any removal from the proper field of our invention. 110

The advantages accruing from the use of the wrench we have described are many. Either 115 end of the chain may be engaged against movement automatically. With an end-to-end reversible double-acting chain we have combined very simple and effective means for permitting the successive use of all portions 120 of the chain. The wrench can be used either side up, and if it be found inexpedient or inconvenient to throw the chain of the wrench over the pipe to be gripped it may be turned under the pipe by merely drawing the chain 125 through its passage without reversing the wrench.

In the form of wrench shown in Figs. 1 to 5 owing to the fact that the opposite grip-faces on the head are substantially in line with 130

the faces of the handle and that the transverse chain-passage is central both with respect to the grip-faces and to the locks it follows that when a flat-link single-course double-acting chain is employed either grip-face can be used to squarely grip a pipe or other article between it and the chain, thus facilitating the use of the wrench with T's and collars on pipes. Since the projecting pintles extend throughout the length of the chain, all portions of the chain can be used by using first one and then the other, thus lengthening the life of the chain.

We claim as our invention—

1. A chain pipe-wrench having, in combination, a handle, a single head at the end of said handle having opposite grip-faces substantially in line with the faces of the handle, a central transverse chain-receiving passage closed at all of its sides and open at its ends, said passage having communicating lateral grooves and having seats near its opposite ends, and said passage being back of the grip-faces of the head, spaced locks on both faces of the wrench behind said passage, and a double-acting flat-link single-course sliding chain adapted to slide freely through said passage from end to end, said chain having projecting pintles throughout its entire length coöperating with said locks, said pintles traveling in said lateral grooves of the chain-passage, and said chain also having stops at opposite ends which cannot pass through said passage, each of which stops is adapted to fit in one of said seats, whereby said chain and either of said grip-faces may squarely grip an article between them.

2. A chain pipe-wrench having, in combination, a handle, a single head at the end of said handle, having opposite grip-faces substantially in line with the faces of the handle, a central transverse chain-receiving passage closed at all of its sides and open at its ends, said passage having communicating lateral grooves and said passage being back of the grip-faces of the head, spaced locks on both faces of the wrench behind said passage, and a double-acting flat-link single-course sliding chain adapted to slide freely through said passage from end to end, said chain having projecting pintles coöperating with said locks, said pintles traveling in said lateral grooves of the chain-passage, and said chain also having stops at opposite ends which cannot pass through said passage, whereby said chain and either of said grip-faces may squarely grip an article between them.

3. A chain pipe-wrench having, in combination, a handle, a single head at the end of said handle, having opposite grip-faces substantially in line with the faces of the handle, a central transverse chain-receiving passage closed at all of its sides and open at its ends, said passage being back of the grip-faces of

the head, spaced locks on both faces of the wrench behind said passage, and a double-acting flat-link single-course sliding chain adapted to slide freely through said passage from end to end, said chain having projecting pintles coöperating with said locks, and said chain also having stops at opposite ends which cannot pass through said passage, whereby said chain and either of said grip-faces may squarely grip an article between them.

4. A chain pipe-wrench having, in combination, a handle, a head at the end of said handle having opposite grip-faces, a transverse chain-receiving passage closed at all of its sides and open at its ends, said passage having lateral grooves and having seats near its opposite ends, spaced locks on both faces of the wrench behind said passage, and a double-acting flat-link single-course sliding chain adapted to slide freely through said passage from end to end, said chain having projecting pintles coöperating with said locks, said pintles traveling in said lateral grooves of the chain-passage, and said chain also having stops at opposite ends which cannot pass through said passage, each of which stops is adapted to fit in one of said seats.

5. A chain pipe-wrench having, in combination, a handle, a head at the end of said handle having opposite grip-faces, a transverse chain-receiving passage closed at all of its sides and open at its ends, said passage having lateral grooves, spaced locks on both faces of the wrench behind said passage, and a double-acting flat-link single-course sliding chain adapted to slide freely through said passage from end to end, said chain having projecting pintles coöperating with said locks, said pintles traveling in said lateral grooves of the chain-passage, and said chain also having stops at opposite ends which cannot pass through said passage.

6. A chain pipe-wrench having, in combination, a handle, a head at the end of said handle having opposite grip-faces, a transverse chain-receiving passage closed at all of its sides and open at its ends, spaced locks on both faces of the wrench behind said passage, and a double-acting flat-link single-course sliding chain adapted to slide freely through said passage from end to end, said chain having projecting pintles coöperating with said locks, and said chain also having stops at opposite ends which cannot pass through said passage.

7. A chain pipe-wrench having, in combination, a handle, a head at the end of said handle having opposite grip-faces, a transverse chain-receiving passage having seats near its opposite ends, said passage being back of the head, a lock on each face of the wrench behind said passage, and a double-acting sliding chain adapted to slide freely through said passage from end to end, said chain coöperating with either of said locks and having a stop at

each end which cannot pass through said passage, each stop being adapted to coöperate with one of said seats.

8. A chain pipe-wrench having, in combination, a handle, a head at the end of said handle having opposite grip-faces, a transverse chain-receiving passage back of the head, a lock on each face of the wrench behind said passage, and a double-acting sliding chain adapted to slide freely through said passage from end to end, said chain coöperating with either of said locks and having a stop at each end which cannot pass through said passage.

9. A chain pipe-wrench having, in combination, a handle, a head having opposite grip-faces, a chain-receiving passage, a lock on each face of the wrench, and a double-acting sliding chain adapted to slide freely through said passage from end to end, said chain coöper-

ating with either of said locks and having a stop at each end which cannot pass through said passage.

10. A chain pipe-wrench having, in combination, a handle, a head having a grip-face, a transverse chain-receiving passage, a lock behind the chain-receiving passage and a sliding chain adapted to slide freely through said passage from end to end, said chain coöperating near one end with said lock and having a stop at its opposite end which cannot pass through said passage.

In testimony whereof we affix our signatures in presence of two witnesses.

GEORGE AMBORN.

GEORGE W. BUFFORD.
